Peter B. Ruch

UNITED STATES PATENT OFFICE.

PETER B. RUCH, OF CUMBERLAND, MARYLAND.

COMPASSES.

1,334,556.

Specification of Letters Patent. Patented Mar. 23, 1920.

Application filed April 1, 1918. Serial No. 226,048.

To all whom it may concern:

Be it known that I, PETER B. RUCH, a citizen of the United States, residing at Cumberland, county of Allegany, and State 5 of Maryland, have invented certain new and useful Improvements in Compasses, of which the following is a specification.

My invention relates to improvements in compasses, and particularly to that class of 10 compasses which may be attached to a pen, pencil, or other marking instrument, and in which the marking instrument itself forms one leg of the compass.

One object of my invention is to provide 15 for a compass which may be formed from, and consists of, a single piece of material, preferably round or flat wire. Another object is to provide a relatively large friction bearing on which the marking instrument is 20 mounted, to facilitate in maintaining adjustments.

I attain these objects by the means set forth in the accompanying drawing in which:

25 Figure 1 is a front elevation showing one form of my improvement applied to a lead pencil.

Fig. 2 is a similar view of a modified form of device.

30 Referring more specifically to the drawing and particularly Fig. 1, A indicates a pencil or marking instrument to which my improvement is to be attached. In carrying out my conception which is susceptible of 35 expression in a variety of forms, I prefer to fashion the device from a single piece of round or flat wire which is bent first into generally circular open ring form the circumference of which, forms the bearing portion 40 B for a marking instrument to lie against and movable along one face thereof; the wire is then bent inwardly and radially at one end of the open ring structure forming a retaining bar C which in form shown 45 in Fig. 1 extends diametrically across the ring member to the outer circumference, and there given a slight bend continuing substantially tangentially as a leg D, the lower end of which is bent slightly inwardly and 50 pointed, that it may constitute the pivot in which the leg of the compass may swing.

The bearing or retaining bar is provided with an offset or bent part in which will be positioned at approximately the generating

center of the circle, this offset acting as a 55 seat and slideway for the marking instrument.

As the device is fashioned from wire preferably having more or less inherent resiliency or elasticity when bent into desired shape, it will be understood, the tendency of the bar C will be to spring inwardly 60 into the flat plane of the ring. As the circumference limits this spring action it will be perfectly obvious that a pencil or marking instrument placed as shown in Fig. 1 65 lying against the circumference and having the bar C extending diametrically across and over the pencil, that it will be held wherever it may be slid the offset providing 70 a seat for the pencil and also a slideway for same, so that it may be adjusted as the pencil wears at its point. The wire is preferably flat, at least on one side, the contact side where the pencil lies against, as this 75 will give greater bearing surface against the pencil.

In the form illustrated in Fig. 2 the essential elements of the device are present but the relative arrangement is somewhat modified as in this form the bearing bar C does not extend entirely across the ring but only slightly beyond the center in one direction; the offset portion however is located at the 80 approximate center of the ring while the 85 circumference itself is prolonged tangentially to form the leg D, as clearly shown in Fig. 2. The action of the bar with the offset is to hold the pencil against the ring in 90 whatever position it may be put.

The various sizes of circles can be drawn with these compasses as the attachment can be slid along on the pencil and the pencil then oscillated with the offset as a center, to 95 practically any angle desired.

The elasticity or resiliency of the wire is such the portions B and C impinge upon the pencil sufficiently to maintain adjustments of the leg D to and from the pencil A and of the ring frame longitudinally of the 100 pencil.

The distinguishing feature of the device shown in the Fig. 1 is that the leg portion D is a continuation of the holding member B while in Fig. 2 the leg portion is a continuation of the bearing or circumferential portion.

When the compass is made of round wire,

the side of the portion B next to the pencil should be slightly flattened to give greater surface in contact with the pencil.

Fig. 1 shows the leg portion as a continuation of the holding portion C, while Fig. 2 shows the leg portion as a continuation of the bearing portion B. The essential features of the device may be embodied in other forms also, and I do not wish to restrict my invention to these forms alone.

I claim:

1. A device as herein characterized comprising a ringlike structure having a flat circular bearing member, a pencil holding member and a leg member respectively disposed radially and angularly relative to the circular bearing member.

2. A device as herein characterized consisting of a flat circular marking instrument bearing member, a marking instrument holding member disposed radially upon said bearing relative to the circumference thereof, said radially disposed member offset to receive and hold such marking instrument against the bearing member, and a leg portion disposed angularly relative to said bearing member.

3. In a device of the class described, the combination with a marking instrument, of a member having a ringlike bearing portion for said instrument, a holding portion extending radially of and opposed to said bearing portion and a portion forming a compass leg extending from said holding portion.

4. A device of the class described com-

prising a flat bearing portion, a marking instrument mounted and oscillatable thereon, a holding portion extending diametrically across said bearing portion, adapted to overlie and maintain the marking instrument in position on the bearing portion, and a portion extending from the holding portion forming a compass leg.

5. In a device of the class described, the combination with a compass leg, a ring shaped instrument-bearing portion, a radial holding portion opposed to said bearing portion and having one of its ends springing from said bearing portion.

6. In a device of the class described, the combination with a lead pencil, of a single piece of wire so formed as to constitute a compass leg and having a circular bearing portion, a radial holding portion opposed to said bearing portion and adapted to maintain the lead pencil in position on said bearing portion.

7. A device as herein characterized comprising a single piece of resilient wire bent to form an extending leg member, a ring structure, and a cross-bar disposed diametrically upon said ring structure.

8. A device as herein characterized, comprising a single piece of wire bent to form an open ring structure, the circumferential portion constituting a bearing member for a marking instrument, a radial cross bar having an offset portion and sprung toward the plane of the ring, and a leg member extending angularly from the cross-bar.

PETER B. RUCH.
